UNITED STATES PATENT OFFICE

FREDRICH J. RODE, OF CHICAGO, ILLINOIS, ASSIGNOR TO MARQUETTE TOOL & MFG. CO.,
OF CHICAGO, ILLINOIS, A CORPORATION OF ILLINOIS

HYDRAULIC CUSHION FOR SHEET-METAL PRESSES

Application filed May 11, 1928. Serial No. 276,868.

This invention relates to improvements in hydraulic cushions particularly adapted, though not necessarily limited in its use in sheet metal presses in which the metal is shaped by means of co-operating dies, one of which is reciprocable toward and away from the other, the work being clamped or held by means of a blank or work holding element that co-operates with the reciprocating die member, the blank or work holder being resisted in its movement in one direction by the said cushion.

Heretofore in cushions of this type the liquid constituting the hydraulic resistance creating medium has been supplied to the cushion from a suitable source, such as a tank, and the liquid in the tank has been subjected to the necessary air pressure for that purpose, and has been supplied from a remote source.

It is one of the objects of the present invention to provide improved means, preferably in the form of a pump device, for circulating the liquid from the tank or source of supply to the cushion to build up the necessary or required pressure and for also returning the blank or work holder to its normal position, the pump being continuously operated, a portion of the liquid circulated thereby being trapped to create the predetermined or necessary resistance pressure, while another portion of the liquid is circulated back to the tank or supply.

A further object of the invention is to provide an improved hydraulic cushioning device of this character in which the circulation of a portion of the liquid will be interrupted while the circulation of another portion of the liquid will remain constant, thereby obviating the necessity of starting and stopping the liquid circulating means or pump, and also the necessity of using two different kinds of pressure to return the pressure pad.

A further object is to provide in an hydraulic cushion of this character improved means whereby the degree of resistance pressure of the liquid to the blank or work holding means may be varied at will at any time

in the cycle of operation of the press to which the cushion is applied.

To the attainment of these ends and the accomplishment of other new and useful objects as will appear, the invention consists in the features of novelty in substantially the construction, combination and arrangement of the several parts hereinafter more fully described and claimed and shown in the accompanying drawings illustrating this invention, and in which

Figure 1 is a view partly in elevation, partly in section, and with parts omitted, of an hydraulic cushion device of this character constructed in accordance with the principles of this invention applied to the press and showing the parts in one position, that is in the position in which the blank or work holding element will be resisted by the liquid pressure.

Figure 2 is a view similar to Figure 1 with parts omitted and on an enlarged scale, showing some of the parts in another position from that shown in Figure 1.

Figure 3 is a top plan view of Figure 1, with parts omitted.

Referring more particularly to the drawings the numeral 10 designates the bed of a press having uprights 11 between which a reciprocating ram 12 operates and which ram carries a movable die member 13.

Mounted upon the bed of the press in any suitable manner is a die 14 with which the die 13 co-operates. A blank or work holding member 15 encompasses the die 14 and co-operates with the die 13 to clamp the work 16 therebetween, and which work is formed over the die 14.

The blank or work holding element 15 is supported by means of suitable pins 17 which pass through the bed plate and are supported by means of a pad or cushioning element 18.

All of the above referred to parts are of the ordinary and well known construction.

The pad or cushioning device 18 in the present form of the invention is in the form of a piston 18 which operates in a cylinder 19, here shown as being embodied in the bed of the press, although the cylinder and piston elements may be separate from the bed

of the press and attached thereto in any suitable manner, well known in this art.

The pad or piston 18 is resisted in its downward movement by means of liquid 20 supplied to the cylinder through an opening 21 and a pipe 22 which receives its supply from a suitable source, such as a tank 23.

Leading from the tank 23 is a pipe 24 which has communication with the inlet side of the casing of a pump 25, preferably of the rotary type.

Leading from the outlet of the pump casing is another pipe 26 which has communication with a coupling or joint 27 and the coupling or joint 27 has communication with a valve casing 28, and with which valve casing 28 the pipe 22 also has communication so that when the pump 25 is operated liquid will be drawn from the tank 23 through the pipe 24, pump casing 25, pipe section 26, coupling 27, valve casing 28 and pipe 22, and delivered into the cylinder 19.

Within the valve casing 28 is a valve 29 preferably of the flap type which co-operates with a seat 30 and is adapted to open, as shown in Figure 1, to permit the liquid to flow therethrough into the pipe 22 in one direction, but will close to prevent the back pressure of the liquid from flowing through the casing 28 back into the pipe 26.

Communicating with the coupling 27 and leading therefrom is a pipe 31 which also has communication with a valve casing 32 in which a valve 33 operates. The valve 33 is controlled by means of a spring 34 set to a predetermined pressure and leading from the valve casing 33 is a pipe 35 which also has communication with the tank or receiver 23 to deliver the liquid back into the tank.

The pump 25 is operated in any suitable manner preferably by means of a motor 36 to the shaft 37 of which the rotor of the pump is connected. The pump is continuously operating and the operation of the mechanism thus far described will be as follows:

Liquid will be drawn from the tank 23 and forced past the valve 29, through the pipe 22 into the cylinder 19, to raise the piston or pad 18 to the position shown in Figure 1, and thereby hold the blank or work holding element 15 substantially flush with the top of the die 14.

The upward movement of the pad or piston 18 is arrested by its engagement with the bottom of the bed plate of the press. As the pump is continuously operating and as the piston or pad 18 is arrested in its upward movement, it will be manifest that unless provision is made to take care of the excess pressure created by the pump and to permit the liquid to flow back into the tank after a predetermined pressure has been obtained, considerable damage will be created. Therefore when the pad or piston 18 is at the limit of its upward movement and the die 13 is

raised, the liquid circulated by the pump 25 will escape through the pipe 31 and will unseat the valve 33 against the stress of the spring 34 to flow through the pipe 35 back into the tank 23.

It will be manifest that with the parts in the position shown in Figure 1, there will be a continuous circulation of a portion of the liquid from the tank 23 back to the tank again while the circulation of the portion of the liquid in advance of the valve 29 will be arrested so that when the pad or piston 18 is lowered during the forming of the work, and against the trapped portion of the liquid, a predetermined resistance pressure will be created against such movement of the pad or piston.

This resistance pressure is controlled by means of a valve 38 which controls a bypass opening 39 leading from the valve casing 28 on the normal outlet side of the valve 29 in the casing 28. The by-pass 39 embodies a pipe 40 which leads around the valve 33 and has communication with a coupling 41 which in turn has communication with the pipe 35 that leads to the tank.

The valve 38 may be held seated under a predetermined pressure in any suitable manner preferably by fluid pressure, and to that end there may be provided a cylinder 42 to which the valve stem 43 of the valve 38 is connected.

The cylinder 42 is supported in any suitable manner preferably by supporting means 44, and within this cylinder is a piston 45 that remains stationary. A pipe 46 leading from any suitable source of fluid pressure supply is connected with the piston 45 and opens therethrough to the lower side of the piston so that when air pressure is admitted through the pipe 46 to the underside of the piston 45 it will move the cylinder 42 downwardly while the piston remains stationary and will thus close the valve 38, holding the valve against its seat under the predetermined pressure exerted between the lower face of the piston 45 and the bottom of the cylinder 42.

This pressure upon the valve 38 is sufficient to maintain the predetermined pressure against the movement of which the pad or piston 18 operates. When, however, the resistance pressure upon the valve 38 is overcome by the pressure of the pad or piston 18 upon the trapped liquid 20, the valve 38 will be unseated and the trapped liquid will then escape through the by-pass opening 39, pipe 40, coupling 41, around the valve 33 and through the pipe 35 back into the tank 23.

The resistance pressure of the valve 38 may be varied as desired to vary the resistance pressure of the liquid 20.

As soon as the pressure of the liquid under the action of the lowering movement of the pad or piston 18 against the valve 38 is over-

come by the pressure in the cylinder 42, the valve 38 will be closed.

As soon as the pressure of the liquid under the lowering movement of the pad or piston 18 upon the valve 29 is overcome, the pump or liquid circulating device 25 will force the liquid which it withdraws from the tank 23 past the valve 29 and into the cylinder 19 to raise the pad or piston 18 and thereby restore 10 the blank or work holding element 15 to its normal position.

By providing pipes 47 which lead from a coupling between the coupling 27 and the valve 28 and by providing additional pipes 15 48 which lead from the coupling 41, as shown in Figure 3, it will be manifest that a series of cushioning devices may be coupled together, thereby extending the scope and capacity of the mechanism.

If desired and in order not to interfere with the lowering movement of the pad or piston 18 a suitable vent opening 49 may be provided for the escape of any air which may find its way into the cylinder 19 on the top 25 side of the pad or piston 18.

While the preferred form of the invention has been herein shown and described, it is to be understood that various changes may be made in the details of construction and in 30 the combination and arrangement of the several parts, within the scope of the claims, without departing from the spirit of this invention.

What is claimed as new is:—

1. A pressure cushion for sheet metal presses embodying cylinder and piston members, hydraulic means for resisting the relative movement of said members in one direction, a container for holding a supply 35 of liquid, a conduit for delivering the liquid from the container to said cushion, means for inducing a circulation of the liquid from the container to the cushion, and means for trapping and maintaining a portion of the liquid against circulation while a continuous circulation of another portion of the liquid will be maintained from the container and back thereto.

2. A pressure cushion for sheet metal 50 presses embodying cylinder and piston members, hydraulic means for resisting the relative movement of said members in one direction, a container for holding a supply of liquid, a conduit for delivering the liquid from the container to said cushion, means for inducing a circulation of the liquid from the container to the cushion, means for trapping and maintaining a portion of the liquid against circulation while a continuous circulation of another portion of the liquid will be maintained from the container and back thereto, means for permitting the escape of 55 said trapped liquid, and variably yielding means for controlling the last recited means.

3. A pressure cushion for sheet metal

presses embodying cylinder and piston members, hydraulic means for resisting the relative movement of said members in one direction, a container for holding a supply of liquid, a conduit for delivering the liquid from 70 said container to the cushion, means for inducing circulation of the liquid through the conduit, means embodying a valve for trapping and maintaining a portion of the liquid against circulation while another portion of 75 the liquid may be circulated from the container and back thereto, and means permitting the trapped liquid to escape and to be circulated back to the container when a predetermined pressure has been obtained upon 80 the trapped liquid, the last recited means embodying a by-pass around said valve and variably yielding means controlling the said by-pass.

4. A pressure cushion for sheet metal 85 presses embodying cylinder and piston members, hydraulic means for resisting the relative movement of said members in one direction, a container for holding a supply of liquid, a conduit for delivering the liquid from 90 said container to the cushion, a continuously operating pump device for circulating the liquid through the conduit, means embodying a valve for trapping and maintaining a portion of the liquid against circulation while 95 another portion of the liquid may be circulated from the container and back thereto, means permitting the trapped liquid to escape and to be circulated back to the container when a predetermined pressure has been obtained upon the trapped liquid, the last recited means embodying a by-pass around said valve, and variably yielding means controlling the said by-pass.

5. A pressure cushion for sheet metal 100 presses embodying cylinder and piston members, hydraulic means for resisting the relative movement of said members in one direction, a conduit for delivering liquid to the cushion, continuously operating means 105 for circulating the liquid through the conduit, means for interrupting the circulation of a portion of said liquid while the circulation of another portion of the liquid remains constant, and means yieldable to a predetermined pressure created upon the quiescent liquid by the relative movement of said members in the opposite direction whereby the last said liquid will escape to be again circulated with the said other portion of the 110 liquid.

6. A pressure cushion for sheet metal 115 presses embodying cylinder and piston members, hydraulic means for resisting the relative movement of said members in one direction, a conduit for delivering liquid to the cushion, continuously operating means for circulating the liquid through the conduit, means for interrupting the circulation of a portion of said liquid while the circulation 120

125

- of another portion of the liquid remains constant, means yieldable to a predetermined pressure created upon the quiescent liquid by the relative movement of said members in the opposite direction whereby the last said liquid will escape to be again circulated with the said other portion of the liquid, and means for varying at will the pressure necessary to overcome the last recited means.
7. A pressure cushion for sheet metal presses embodying cylinder and piston members, hydraulic means for resisting the relative movement of said members in one direction, a conduit for supplying liquid to the cushion, mechanical means for inducing circulation through the conduit, a valve in the conduit for trapping a portion of the liquid to establish a predetermined resistance pressure to the relative movement of said members in the opposite direction, a branch leading from said conduit on one side of the valve, a by-pass leading around said valve from the other side thereof and communicating with said branch, means for controlling the by-pass, and variably yielding means for controlling the last said means.
8. A pressure cushion for sheet metal presses embodying cylinder and piston members, hydraulic means for resisting the relative movement of said members in one direction, a conduit for supplying liquid to the cushion, mechanical means for inducing circulation through the conduit, a valve in the conduit for trapping a portion of the liquid to establish a predetermined resistance pressure to the relative movement of said members in the opposite direction, a branch leading from said conduit on one side of the valve, a by-pass leading around said valve from the other side thereof and communicating with said branch, means for controlling the by-pass, and fluid pressure means for controlling the last said means.
9. A pressure cushion for sheet metal presses embodying cylinder and piston members, hydraulic means for resisting the relative movement of said members in one direction, a conduit for supplying liquid to the cushion, mechanical means for inducing circulation through the conduit, a valve in the conduit for trapping a portion of the liquid to establish a predetermined resistance pressure to the relative movement of said members in the opposite direction, a branch leading from said conduit on one side of the valve, a by-pass leading around said valve from the other side thereof and communicating with said branch, means for controlling the by-pass, and variably yielding means for controlling the last said means, the said liquid circulating means being also operable to cause the liquid to impart a relative movement to the cylinder and piston members in one direction.
10. A pressure cushion for sheet metal presses embodying a work holding element, a plunger for resisting the movement of said element in one direction, a predetermined supply of liquid operating upon said plunger, mechanical means for maintaining a portion of the liquid in circulation, means for trapping a portion of the liquid, and means for controlling at will the degree of pressure of the said trapped liquid against which the said plunger is operable by the pressure of the said work holding element.
11. A pressure cushion for sheet metal presses embodying a work holding element, a plunger for resisting the movement of said element in one direction, a predetermined supply of liquid operating upon said plunger, constantly operating mechanical means for maintaining a portion of the liquid in circulation, means for trapping a portion of the liquid, and means for controlling at will the degree of pressure of the said trapped liquid against which the said plunger is operable by the pressure of the said work holding element.
12. A pressure cushion for sheet metal presses embodying a work holding element, a plunger for resisting the movement of said element in one direction, a predetermined supply of liquid operating upon said plunger, mechanical means for maintaining a portion of the liquid in circulation, means for trapping a portion of the liquid, an escape passage for the trapped liquid, and means for controlling the said escape passage whereby the degree of resistance pressure of the trapped liquid against the plunger is operable by the pressure of the work holding element may be varied.
13. A pressure cushion for sheet metal presses embodying a work holding element, a plunger for resisting the movement of said element in one direction, a container for containing a predetermined supply of liquid, a conduit for delivering the liquid from the container to operate upon the plunger, means connected with the conduit for circulating the liquid therein, a valve in the conduit for trapping a portion of the liquid to establish a resistance pressure against which the plunger is operable, a by-pass leading around said valve to permit the trapped liquid to escape, means for controlling said by-pass to establish a predetermined resistance pressure of the liquid against which the piston operates, a branch pipe also leading from said conduit to the container whereby a portion of the liquid will be maintained in circulation, and means for controlling said branch pipe.
14. A pressure cushion for sheet metal presses embodying a work holding element, a plunger for resisting the movement of said element in one direction, a container for containing a predetermined supply of liquid, a conduit for delivering the liquid from the

container to operate upon the plunger, means connected with the conduit for circulating the liquid therein, a valve in the conduit for trapping a portion of the liquid
5 to establish a resistance pressure against which the plunger is operable, a by-pass leading around said valve to permit the trapped liquid to escape, means for controlling said by-pass to establish a predetermined resistance pressure of the liquid
10 against which the piston operates, a branch pipe also leading from said conduit to the container whereby a portion of the liquid will be maintained in circulation, and means
15 for controlling said branch pipe, the said liquid circulating means also operating to cause the liquid to directly act upon said plunger for returning the work holder to normal position.

20 In testimony whereof I have signed my name to this specification, on this 8th day of May, A. D. 1928.
